US00D619102S

(12) **United States Design Patent**
Hanses

(10) **Patent No.:** **US D619,102 S**
(45) **Date of Patent:** **** Jul. 6, 2010**

(54) **ELECTRICAL CONTROLLER DEVICE**

(75) Inventor: **Markus Hanses**, Hoexter (DE)

(73) Assignee: **Phoenix Contact GmbH & Co. KG**,
Blomberg (DE)

(**) Term: **14 Years**

(21) Appl. No.: **29/327,433**

(22) Filed: **Nov. 5, 2008**

(30) **Foreign Application Priority Data**

May 5, 2008 (EP) 000928478

(51) **LOC (9) Cl.** 13-03

(52) **U.S. Cl.** **D13/160**

(57) **CLAIM**

The ornamental design for electrical controller device, as shown and described.

DESCRIPTION

FIG. 1 is a top, front, and left side perspective view of an embodiment of my new design for an electrical controller device;

FIG. 2 is a left side view thereof;

FIG. 3 is a rear view thereof;

FIG. 4 is front view thereof;

FIG. 5 is right side view thereof;

FIG. 6 is a bottom view thereof; and,

FIG. 7 is a top view thereof.

The broken line portion in the drawing views is included to show unclaimed subject matter only and forms no part of the claimed design.
